UNITED STATES PATENT OFFICE.

JOHN HARRIS AND JOSIAH LUCAS, OF BRANTFORD, ONTARIO, CANADA,
ASSIGNORS TO A. HARRIS, SON & CO., (LIMITED,) OF SAME PLACE.

HARVESTER-BINDER.

SPECIFICATION forming part of Letters Patent No. 349,994, dated September 28, 1886.

Application filed May 14, 1885. Serial No. 165,539. (No model.)

To all whom it may concern:

Be it known that we, JOHN HARRIS, of the city of Brantford, in the county of Brant, in the Province of Ontario, Canada, and JOSIAH LUCAS, of the same place, have jointly invented certain new and useful Improvements in Harvester-Binders; and we do hereby declare that the following is a full, clear, and exact description of the same.

10 The object of the invention is to produce a harvester-binder which can be more easily folded up than those at present in use, so that the machine, when folded up, should occupy a narrower space in width than usual, so that 15 a farmer may be enabled to drive it through a narrower gateway; and it consists in pivoting and supporting the packer-deck and packing and binding apparatus in a bearing whose center is that of the packer-shaft, thus 20 affording more of a rocking or rolling motion and less leverage during the act of folding than if the folding apparatus were hinged at its inner side.

Figure 1 is a perspective view of the machine when the packing and binding apparatus have been let down into position for work. In this view part of the table and cross-sill are broken away, so as to show one of the movable hangers in the position it assumes 30 when the machine is ready for work. Fig. 2 is a perspective view of the machine when the packing and binding apparatus are rolled up, being held in this position by a hook attached to the main frame hooked into an eye 35 in the knotted-shaft. Fig. 3 is a perspective view of the clearing-roller A, showing the lugs or projections and the iron straps and their mode of attachment to the tie-piece of the partition adjoining the canvas. Fig. 4 is 40 a cross-section through said roller and the fixed deck B. Fig. 5 is a side elevation showing the packer-shaft and its mode of support, the movable hangers, and the inner and outer tubes supporting the frame-work of the packer-deck. In this view the machine is shown as 45 when folded up, the said packer-shaft acting as the central or pivoting support during the operation of folding up the binder-table of the machine.

In this machine neither the squared end of 50 the packer-shaft nor the sheet-iron cover near the elevating-canvas need be removed or disconnected previous to folding up the binder, and will admit of being rolled or folded by the strength of a boy, owing to the lesser leverage and the balancing motion caused by the central pivoting. 55

The slanting deck in this machine is a fixture, and we have added a clearing-roller, A, with projecting lugs *a* and straps *b*, to assist 60 in forcing the grain over it into the packers.

Similar letters of reference indicate corresponding parts in the several figures.

A is the extra or clearing roller, which is about on a horizontal line with the top roller 65 of the lower elevating-canvas, so as to prevent the grain lodging when delivered from the elevating-canvas, and it is designed, in connection with the lugs or projections *a* and straps *b*, to assist in carrying grain over the 70 surface of the deck B to the packers. This roller derives its motion from a sprocket-wheel, C, (see Fig. 1,) and short chain *c*, connected with a sprocket-wheel, X, on the spindle of the upper roller of the lower elevating- 75 canvas. This clearing-roller is supported by metal spindles running in iron boxes fastened to the harvester-frame. On this clearing-roller are two rows of lugs, *a*, placed on either side, each row containing about five or six. 80 Their function is to prevent the grain lodging when delivered from the elevating-canvas, and to assist in carrying it across the standing-deck B to the packers. At the rear end of this clearing-roller a couple of these lugs 85 are omitted, so that they may not injure the heads of the grain. These lugs are placed in line, with spaces between, through which pass straps *b*, of the form shown in Fig. 4. The lower ends of the straps are fastened to the 90 cross-tie piece on the main frame of the harvester, the other ends being loose and resting on the top of the slanting deck B. There are two or three straps which run over that part of the rear end of the roller where there are 95 no lugs. A lug at the front end of the roller is also omitted, so as to leave room for the canvas-adjuster. These straps are intended

to prevent the grain falling between the slanting deck and the roller.

F and G are hollow cast-iron pillars. They both work laterally on a T-shaped slide bolted 5 to the top of the cross-sill H, and move along with the rest of the frame-work when the machine is adjusted by means of the lever-arm I, connected to a casting at the rear end of the hollow inner tube, J. In this way the machine 10 is adapted to pack and bind longer or shorter grain, as occasion may require. Cross-ties V brace the pillars F and G together laterally, and these pillars have claws f, which grasp the upper part of the flange g on the slides K, 15 thus keeping the pillars F and G in position directly under the round end L of the packer-shaft, so that they cannot be displaced. The upper ends of these supports or pillars are furnished with jaws h, through which pass pins, 20 thus inclosing the round end L of the packer-shaft. The upper ends of the supports F and G are also hollowed out in a circular form, so as to form beds or cradles for the circular hubs, 25 which form part of the iron frame-work t of the packer-deck.

j is a lug on the front pillar, F, for the purpose of causing the pillar to move with the binding mechanism when adjusted by the lever-arm I.

30 M is a square bar sliding through a square hole in a sprocket-wheel. This sprocket-wheel runs in a bearing, l, attached to the main frame, and communicates its motion, by means of the square bar M and round shaft L, 35 to the packing and binding mechanisms, respectively. The other or inner end of this square bar fits into a square hole in the end of the double packer-crank, and is secured in position by the spring m, having at its end a 40 lug, which fits into a hole in the double packer-crank. The round end L of the packer-shaft is supported, as before mentioned, directly from underneath by the supporters F and G, and this round shaft L and square bar 45 M are in a direct line, and always retain their relative position, whether the machine is folded up or not. The two shafts L and M and double crank connecting them may be termed the "packer-shaft," and on this packer-shaft, as 50 a center, the binder-table is turned.

O and P are two movable hangers placed in the relative position shown in the drawings. The hanger O, near the front end of the machine, is the larger of the two. Their upper 55 ends are formed into loops q', through which loops pass the inner tube, J. The other or lower ends of these hangers are bent, forming toes q, which act as stops against the hollow casting r on the inner face of the cross-sill H. 60 These hangers work through castings s and r, and are made of such a length that when the machine is unrolled and ready for work these toes or stops q rest against the bottom of the castings r on the inner face of the cross-sill, as 65 mentioned, the other casting, s, being bolted to the outer face of the breast-board Q.

J is an inner tube or pipe extending the full

width of the packer-deck and rigidly connected with the iron frame-work t by fitting closely through holes cast in said frame-work t. The 70 rear end is connected by the lever arm I to the adjuster, as before mentioned.

R is an outer tube, made and connected to the frame-work in a manner similar to the inner tube, J. On these two tubes J and R and 75 on the iron-work t rests the wooden frame-work of the binder-table.

When the binder-table is folded up, as shown in Fig. 2, all that is necessary to do in order to throw the machine into working position, as shown in Fig. 1, is to unhook the hook before referred to, (which is attached to the main frame and hooked into an eye on the knotted-shaft,) and by slightly tilting the packing and binding apparatus it falls or rolls 80 round the packer-shaft into the position shown in Fig. 1, the movable hangers O and P moving in the manner as indicated in the drawings, while the packing or binding apparatus, having the greater part of the weight on the 85 outer side of the packer-shaft, retains its position, after having been rolled, by the force of 90 gravity.

The invention is designed to furnish a machine to the public which will do its work in 95 a simple, expeditious, and effective manner; which will occupy less width in passing through a gateway, and which, owing to the method of central pivoting, can be rolled or folded without any exertion and without the 100 detachment of any of its parts, as has hitherto been the case.

We do not claim, broadly, a clearing-roller arranged between the top of the elevating-canvas and the binding-table, for we are aware 105 that such has been proposed.

What we claim as our invention is—

1. The combination, with the harvester and the binding-table thereof, of the roller A, having lugs a, and the straps b, arranged to rest 110 between said lugs, and having their lower ends fastened to the main frame and their upper ends loose and resting on the top of the slanting deck B, the rear end of said roller having smooth periphery, substantially as and for the 115 purpose specified.

2. The combination, with the packer-shaft and the packing and binding apparatus, of bearings arranged to support the frame-work of said binding and packing apparatus, all 120 constructed and arranged substantially as described, whereby the same may be folded on a pivot whose center shall correspond with that of said packer-shaft, substantially as described.

3. The binding-table and pillars arranged 125 to support and form pivot-bearings for the frame carrying the packing and binding apparatus, in combination with the lug j on one of said pillars and bearings formed on the cross-sill in such a manner that the pillars may be moved laterally with the binder-table without disconnecting them from the cross-sill, 130 substantially as and for the purpose specified.

4. The stop-rod O, having a looped end, q',

through which the pipe J passes, and a toe or enlargement at its other end, in combination with the binder-platform, the shaft on which it is pivoted, the bar J, and a guide arranged 5 to hold the hanger O to the sill H, while permitting it to have sufficient longitudinal movement to allow of the rolling of the table.

5. The stop-rod O, having a looped end, q' , and a toe, q , at its other end, in combination

with the binder-platform, the shaft on which it is pivoted, the bar J, and the bearings or castings r and s , the whole being arranged substantially as and for the purpose specified.

JOHN HARRIS.
JOSIAH LUCAS.
